UNITED STATES PATENT OFFICE.

HOWARD EDWIN BEDFORD, OF LONDON, ENGLAND, ASSIGNEE, BY MESNE ASSIGNMENTS, TO PYRENE MINIMAX CORPORATION, OF NEWARK, NEW JERSEY, A CORPORATION OF DELAWARE.

FIRE-EXTINGUISHING PLANT.

Application filed June 10, 1925, Serial No. 36,276, and in Great Britain June 14, 1924.

This invention relates to fire extinguishing apparatus of the class wherein an acid solution and an alkaline solution in conjunction with a foam producing agent produce a foam 5 jet which is ejected through a nozzle. The object of the present invention is to enable steam ejectors to be employed for propelling the two solutions to the nozzle in such a way that the latter can be shut off for maneuvering purposes, for example, on board ship, without breaking or interrupting the thread of the steam ejectors.

With this aim in view according to the present invention the two solutions are drawn 15 from their respective tanks each by means of a steam ejector and forced into the respective pipe mains by means of which the solutions are carried to the foam nozzle; the pipes through which the solutions are taken 20 off from the tanks are each provided with a check valve and a by-pass tube of relatively small bore is furnished from the delivery side of each ejector nozzle and delivers into the upper part of the respective solution 25 tanks. By this means when the nozzle is shut down with the steam on, any surplus solution sucked through is returned to the upper part of the respective tank; the by-pass in each case is only of sufficient cross-section to 30 prevent an interruption or break in the jet of the ejector.

In order that the invention may be clearly understood and may be readily carried into practice, an installation constructed in accordance therewith will now be described 35 more fully with reference to the accompanying drawings, wherein:

Figure 1 is a front elevation of the solution tanks and their fittings showing the tank 40 for the acid solution in section;

Figure 2 is an elevation from the right-hand side of Figure 1;

Figure 3 is a plan of Figure 1;

Figure 4 is a horizontal central section 45 showing the stop valve with its hand wheel removed;

Figure 5 is a central vertical section through one of the two check valves fitted in the two steam branches;

Figure 6 is an elevation from the delivery 50 end of one of the steam ejectors or jet pumps, to wit, the ejector shown at the left in Figure 3;

Figure 7 is a vertical section of the same 55 on the line VII—VII in Figure 6;

Figure 8 is a central horizontal section of Figure 6, and finally

Figure 9 is a central vertical section 60 through one of the check valves located in the off-take pipes from the solution tanks.

Referring first to the general arrangement shown in Figures 1 to 3, the system is arranged to employ two effective solutions, for example, an acid solution of aluminum sulphate and an alkaline solution of sodium bicarbonate, the latter also containing the foam producing agent, such as licorice or logwood extract. These solutions are contained in two tanks 1, 2 which are made D-shape in plan or horizontal section and are placed back to back as seen in Figure 3 in order to economize space. The acid tank 1 is shown provided with a lead lining 3 to resist corrosion. These tanks do not need to be of such careful manufacture with the joints as carefully 70 tested as was essential in previous systems wherein the liquid in the tanks was ejected by means of steam pressure admitted to the tanks.

The steam supply pipe 4 is brought down 80 into a position just above the dividing wall or partition between the tanks 1 and 2 and has two branches 5, 6 each of which passes over the top of one of the tanks 1, 2 and the steam supply pipe 4 is furnished with a 85 regulating valve 7 at its junction with the two branches 5, 6. It is essential that this steam regulating valve shall be capable of very fine regulation at the moment of opening, although such fine regulation is not so 90 necessary when it is well open. The details of a suitable valve generally of known form for use in this connection are shown in Figure 4. The valve itself is in the form of a tubular plunger or petticoat 8 fitting within 95 the bore of the seating 9 and the plunger has control ports 10 of triangular shape so that on the first opening of the valve the steam from the pipe 4 escapes into the branches 5 and 6, gradually through the apex of the triangular port 10 so that the regulation at the moment of opening is a fine regulation, but a more rapid increase in opening is obtained 100 when the valve is fairly fully open. An alternative arrangement which will produce 105 a similar effect and is satisfactory for the

present purpose, although rather more complicated, is a stop valve provided with a differential screw stem to allow of fine adjustment, but the arrangement illustrated is preferred on account of its simplicity.

The steam supply to the pipe 4 may be normally at a pressure from 40 to 60 pounds per square inch, or even as high as 100 pounds per square inch, but the installation 10 is capable of being worked with a steam pressure as low as 30 pounds per square inch. Each of the branches 5 and 6 of the steam pipe is furnished with a check or non-return steam valve 11 so that should the steam pressure 15 entirely fail suddenly, there is no risk of acid or alkaline liquid flowing back through the stop valve 7 into the steam pipe 4. Details of the check valves 11 are illustrated in Figure 5 wherein the normal direction of flow of steam is indicated by the arrows. The valve proper closes normally due to its own weight and is raised and opened by the steam pressure, but any tendency to backward flow is prevented by immediate closing of the valve automatically. The branches 5, 6 of the steam pipe after leaving the check valves 11 are each turned downwardly and then rearwardly and immediately after turning rearwardly each has 30 inserted in its length a steam ejector or jet pump 12, which although of quite usual construction is illustrated in greater detail in Figures 6 to 8. These ejectors serve to set up a suction in the annular space around 35 their nozzles 13. Each of the ejectors 12 is connected to a hollow fitting 14 which serves to connect the annular suction space around the respective nozzles 13 with an off-take pipe 15 best seen in Figure 1. The lower 40 ends of the pipes 15 are perforated and terminate in small wells 26 in the bottom of the tanks 1, 2 arranged so that the whole of the liquid in each tank can be substantially drawn up through the pipes 15. The purpose 45 of the steam jets 13 is therefore to create a suction in the two off-take pipes 15 so that the two solutions are respectively drawn up from the tanks 1, 2 into the steam pipes 5, 6, to the outlet ends of which are 50 connected liquid supply mains 5' and 6'. These supply mains 5' and 6' are united, as shown at 30, and are connected with a suitable mixing nozzle 31 which is provided with a control valve 32. When the nozzle 55 31 is open and in operation, there is a continuous flow of steam through each of the ejector nozzles 13 thus producing a continuous flow of the acid and alkaline solutions in the two pipes 5, 6 and a continuous production 60 of foam in the nozzle 31 to be projected therefrom in a stream on to the fire which it is desired to extinguish.

In practical use, particularly on board ship, it is necessary to shut off the nozzle 31 65 occasionally while the operator manœuvres

it into a fresh position. As already mentioned, it would be a nuisance if every time this happened it was necessary to shut off the steam by means of the regulating stop valve 7 and in order to make it possible to 70 shut off the nozzle 31 without forcing the steam passing through the valve 7 downwards by way of the off-take pipes 15 into the solution tanks 1, 2, a check valve or non-return valve 16, shown in Figure 9, is located in each of the fittings 14 so as to shut automatically when the suction ceases and steam pressure is set up above the valves 16. Each of the check valves 16 is of similar construction to the valve 11 shown in Figure 5, 80 normally closing by its own weight but in operation drawn up and opened by the suction created by the nozzles 13. If the steam were allowed to pass through the off-take pipes 15 into the tanks 1, 2 when the nozzle 31 was 85 shut off, not only would the solution in each tank be overheated but all the pipes in the neighbourhood would be warmed up and would make it difficult to start the jets afresh after an interval and such restarting would 90 not be sufficiently rapid. In order to prevent the jet breaking when the nozzle 31 is shut off, a by-pass of small cross-section is employed to connect the delivery side of each 95 of the ejectors 12 to the upper part of the respective solution tank. In the form illustrated, this by-pass consists of a small port or passage 19 cast in the end flange 20 of each of the ejectors 12, the flange 20 in each case being cast with a foot 21 by means of 100 which each ejector is secured to the top of the respective tank 1 or 2. The by-pass passages 19 are of small cross-section, in fact the cross-section of each is only just sufficient to prevent the jet breaking when 105 the nozzle 31 is shut off. Any surplus solution sucked through the off-take pipe 15 when the nozzle 31 is shut off with the steam pressure turned on is returned to the upper part of the tank in question through the by-pass passage 19. This arrangement has the further advantage that it sets up a certain amount of stirring or agitation of the solutions in the two tanks because the solution 110 by-passed is taken from the lower part of 115 the tank by the off-take pipe 15 and is returned to the upper part through the passage 19; this has the tendency of counter-acting the deposit of sediment at the bottom of the tank.

Having thus described my invention, what I claim as new and desire to secure by Letters Patent is:—

1. In a fire extinguishing plant having a pair of tanks adapted for the reception of two separate solutions to be delivered to a point without said tanks and there commingled and expelled through a nozzle adapted to be opened and closed to control such delivery, a fluid-operated ejector pump 125 130

for each tank, a delivery main leading from the delivery end of each pump to said point of mixing, connections leading from the bottoms of said tanks to the inlet ends of said pumps, and by-passes leading from the upper ends of said tanks to the outlet ends of said pumps to afford an escape for the operating fluid when said nozzle is closed and to permit the return of solution to said tanks irrespective of whether or not said nozzle is open or closed.

2. In a fire extinguishing plant having a pair of tanks adapted for the reception of two separate solutions to be delivered to a point without said tanks and there commingled and expelled through a nozzle adapted to be opened and closed to control such delivery, a fluid-operated ejector pump for each tank, a delivery main leading from the delivery end of each pump to said point of mixing, connections leading from the bottoms of said tanks to the inlet ends of said pumps, and by-passes leading from the upper ends of said tanks to the outlet ends of said pumps to afford an escape for the operating fluid when said nozzle is closed and to permit the return of solution to said tanks irrespective of whether or not said nozzle is open or closed, and automatically actuated non-return valves in said connections adapted to fully open when said nozzle is fully opened and to only partially close upon fully closing said nozzle.

3. In a fire extinguishing plant having a pair of tanks adapted for the reception of two separate solutions to be delivered to a point without said tanks and there commingled and expelled through a nozzle adapted to be opened and closed to control such delivery, a fluid-operated ejector pump for each tank, a delivery main leading from the delivery end of each pump to said point

of mixing, connections leading from the bottoms of said tanks to the inlet ends of said pumps, and by-passes leading from the upper ends of said tanks to the outlet ends of said pumps to afford an escape for the operating fluid when said nozzle is closed and to permit the return of solution to said tanks irrespective of whether or not said nozzle is open or closed, means common to both of said pumps for supplying an operating fluid thereto, and non-return valves intermediate said common means and said pumps.

4. In a fire extinguishing plant having a pair of tanks adapted for the reception of two separate solutions to be delivered to a point without said tanks and there commingled and expelled through a nozzle adapted to be opened and closed to control such delivery, a fluid-operated ejector pump for each tank, a delivery main leading from the delivery end of each pump to said point of mixing, connections leading from the bottoms of said tanks to the inlet ends of said pumps, and by-passes leading from the upper ends of said tanks to the outlet ends of said pumps to afford an escape for the operating fluid when said nozzle is closed and to permit the return of solution to said tanks irrespective of whether or not said nozzle is open or closed, automatically actuated non-return valves in said connections adapted to fully open when said nozzle is fully opened and to only partially close upon fully closing said nozzle, means common to both of said pumps for supplying an operating fluid thereto, and non-return valves intermediate said common means and said pumps.

In witness whereof, I hereunto subscribe my name this 29th day of May A. D. 1925.

HOWARD EDWIN BEDFORD.
